Howard E. Thompson
ATTORNEY.

UNITED STATES PATENT OFFICE

WILLIAM I. SILVERSTEIN, OF BROOKLYN, NEW YORK

REVERSIBLE CAP

Application filed May 31, 1929. Serial No. 367,246.

This invention relates to caps and particularly to what are known as peaked caps and to the provision of an article of apparel of this class which is so constructed as to 5 permit a double use thereof by simply turning the crown of the cap inside out, and still more especially to the construction of caps of the class described, designed particularly for use by hunters; and the object of the 10 invention is to provide a cap structure of the class and for the purpose specified, the crown and head encircling band portion of which is so constructed as to readily facilitate the reversible use of the cap, the peak 15 of the cap being preferably constructed of relatively stiff but flexible material to compensate for the dual use of the cap; a further object being to provide two distinct facing materials employed in the construction 20 of the cap, one of which is preferably of a bright red color to facilitate the use of the cap by hunters with the bright red facing exposed externally of the cap and over the entire structure thereof; a further object 25 being to provide a cap of the class described with a neck encircling and ear covering band or flap which may be arranged in a downwardly extending position in both uses of the cap or folded upon the crown portion 30 thereof; a further object being to provide a simple means of attaching the inner and outer facings and separate sections of the crown portion of the cap and for reinforcing and strengthening the same; and with these 35 and other objects in view, the invention consists in an article of apparel of the class specified which is simple in construction, efficient in use, and which is constructed as hereinafter described and claimed.

Fig. 1 is a perspective view of a cap made according to my invention, illustrating one position of its use.

Fig. 2 is a view similar to Fig. 1, but showing the cap inverted.

Fig. 3 is a partial section on the line 3-3 of Fig. 1 on an enlarged scale.

Fig. 4 is a partial section on the line 4-4 of Fig. 1 on an enlarged scale; and,

Fig. 5 is a partial section on the line 5-5 of Fig. 1 on an enlarged scale.

While my improved cap may be used for many purposes, one of its distinctive uses is in the form of a hunter's cap. In caps of this class as heretofore constructed, it has 55 been customary to provide the outer wall structure of the crown portion with a member movable into two different positions so as to provide a cap, the crown portion of which may be all red in one use and of another contrasting color in the other use thereof. This type of cap is cumbersome and awkward to handle as well as uncomfortable in use, especially by virtue of the bulk in the wall structure of the cap especially where the 60 movable crown portion is arranged; whereas in my improved construction, these objectionable features are obviated and a cap of greater utility for the purpose intended is 65 provided.

In the drawings, 10 represents the crown portion of the cap, 11 the peak, and 12 the neck and ear covering band. In the construction shown, an annular head encircling band 13 is disposed between the crown portion 10 and the peak 11 and band 12. The crown 10 in the construction shown is fashioned from inner and outer facings 10a and 10b respectively, each facing being composed of separate pieces of material fashioned to the desired form in properly shaping the cap in accordance with conventional methods and the separate pieces are secured together where they join by reinforcing and coupling strips 10c and 10d, the strips 10c being arranged on the facings 10a and the strips 10d on the facings 10b, note Fig. 3. Stitchings 14 at opposite sides of the strips 10c and 10d serve to couple the facings together and the separate pieces of each facing 85 90

to each other. It is also preferred that each or both facings be waterproofed in any desired manner, the waterproofing being indicated between said facings at 15, note Fig. 3 of the drawings.

For the purpose of description, the facing 10a, termed the inner facing, will be constructed from a bright red material preferably of a soft texture, whereas the facing 10b will be of any other color to suit the taste of the purchaser and may be constructed of a similar or contrasting material. For the purpose of illustration, the facing 10b may be constructed of brown khaki material, it being understood that the strips 10c and 10d will be composed of the same material or a material of the same color as that of their corresponding facings so that the entire crown portion will have one solid color in both uses thereof.

The head encircling band 13 is also composed of inner and outer strips 13a and 13b, the strip 13a being of the same color as the facing 10a and the strip 13b the same color as the facing 10b, and one edge of each of these strips is attached to the separate facings on the line of stitching 16, note Fig. 4 of the drawings.

The peak 11 also has inner and outer facings 11a and 11b of colors corresponding to that of the facings 10a and 13a, 10b—13b. Disposed between the facings 11a and 11b is a relatively thick stiffening body 11c to maintain the peak in proper shape, this body being preferably of a flexible nature to permit the free flexing thereof in the dual use of the cap without danger of breaking or destroying said peak, the head end portion of the peak being arranged between the strips 13a and 13b of the band 13 and stitched thereto by a line of stitching 17 which also serves to attach the band or flap 12 as later described.

The peripheral edge of the peak 11 is covered by a finishing strip 18 stitched thereto as seen at 19. This facing or edging strip may be of any desired material and color and preferably a material of strong and durable texture such as for example as a strip of leather. The neck and ear band 12 is also composed of inner and outer facings 12a and 12b of colors corresponding to the other facings; and a coupling strip 20 consisting of inner and outer facings 20a and 20b is employed for coupling the flap 12 with the lower edge of the head encircling band 13, the facings 20a and 20b being disposed between the facings 13a and 13b and stitched thereto by the line of stitching 17 as above stated, whereas the facings 20a and 20b overlie the facings 12a and 12b and are stitched thereto by the line of stitching 21.

The flap 12 is also preferably waterproofed as seen at 12c, and in this connection, it will also be noted that the water-

proofing 11d is disposed between the facings 11a—11b and the stiffening member 11c. The free edge of the flap 12 is protected by a finishing strip 22 similar to the strip 18 and this is stitched to the flap by the line of stitching 23. The purpose of the attaching strip 20 is to provide for the free flexing of the flap 12 so as to arrange the same in a downwardly extended position as seen in full lines in Figs. 1 and 2 of the drawings and to permit said flap to be folded upon the crown portion of the cap as indicated in dotted lines in said figures.

From the foregoing description, the use of my improved cap will be readily understood especially when taken in connection with the accompanying drawings and the following statement. For purposes of description, the cap as seen in Fig. 1, has its normal side exposed outwardly as the cap would be used ordinarily, the color being suitable to the taste of the wearer or purchaser whereas in inverting the cap or turning the crown portion inside out, the distinct and desired color will be exposed on the entire surface of the cap. In the case of hunters' caps, the color of the exposed material will be of a bright red, the color which is conventionally used by hunters.

In inverting the cap, it will be apparent that no change in the size of the cap has been effected nor has the inverting of the cap introduced any added bulk to the cap structure or any other inconvenience to the user. By providing the band 13, the reversing of the cap may be readily accomplished.

It will be understood that my invention is not necessarily limited to the provision of the neck and ear flap 12 nor to the specific manner of shaping and constructing the crown portion of the cap and the attachment of the peak thereto, and various other changes in and modifications of the construction herein shown and described, may be made within the scope of the appended claims without departing from the spirit of my invention or sacrificing its advantages.

Having fully described by invention, what I claim as new and desire to secure by Letters Patent, is:—

A reversible peak cap of the class described, the crown portion of which is constructed of independent and contrasting inner and outer facings, each of said facings being adapted to be arranged externally of the cap, a relatively wide, flexible head encircling band exposed in both uses of the cap and having facings corresponding to that of the crown portion, said band extending entirely around and being attached to the lower edge of the crown portion, and a peak having facings corresponding to that of the crown portion and attached to the free edge of said band at the front and side portions thereof, whereby said peak is flexibly

coupled with the crown permitting the free reversal of said cap, an ear and neck flap coupled with the lower edge of said band at the rear and side edges thereof and movably disposed with reference thereto and means disposed between the facings of the separate parts of the cap for rendering said cap moisture-proof in both uses thereof.

In testimony that I claim the foregoing as my invention I have signed my name this 27th day of May 1929.

WILLIAM I. SILVERSTEIN.
